(57) CLAIM

The ornamental design for a board clip for box, as shown and described.

DESCRIPTION

FIG. 1 is a perspective view of a board clip for box showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a board clip for box in a different configuration thereof; and,

FIG. 9 is another perspective view of a board clip for box in another configuration.

The broken lines illustrate portions of the board clip for box that form no part of the claimed design.
